UNITED STATES PATENT OFFICE.

WILLIAM H. CARRUTHERS, OF CHICAGO, ILLINOIS.

NUT-LOCK.

SPECIFICATION forming part of Letters Patent No. 659,466, dated October 9, 1900.

Application filed January 20, 1900. Serial No. 2,088. (No model.)

To all whom it may concern:

Be it known that I, WILLIAM H. CARRUTHERS, a citizen of the United States, residing at Chicago, in the county of Cook and State 5 of Illinois, have invented certain new and useful Improvements in Nut-Locks, of which the following is a specification.

This invention relates to improvements in nut-locks of that class in which a spring- 10 metal wire or bar of suitable cross-section is formed into a spring-ring adapted to be screwed upon the threads of a bolt, so as to follow and be seated within the helical groove thereof. Difficulty has heretofore been found 15 in manipulating nut-locks of this character during the operation of placing them upon or removing them from the bolts; and the object of the present invention is to provide improvements which enable such nut-locks 20 to be more easily manipulated and the difficulties referred to be overcome; and to this end it consists in certain peculiarities of construction at the extremities or ends of the spring-ring which enable the expander or 25 other tool used in applying or removing the device to be applied to better advantage and which go to produce a more finished article, less liable to catch and hold the clothing or 30 dirt or straw with which the bolt may be brought into proximity.

The invention will be more fully understood from the following description of the construction illustrated in the accompanying drawings, in which—

35 Figure 1 is a face view of one form of nut-lock constructed in accordance with my invention. Figs. 2 and 3 are sectional views thereof, taken on lines 2 2 and 3 3, respectively, of Fig. 1. Fig. 4 is a face view of another form of nut-lock embodying the invention. Fig. 5 is an edge elevation thereof. Fig. 6 is a section thereof, taken on line 6 6 of Fig. 4. Fig. 7 is a face view of a nut-lock 40 similar to that shown in Fig. 4, but made of metal of different cross-section. Fig. 8 is an edge elevation thereof. Fig. 9 is a section thereof taken on line 9 9. Fig. 10 shows several different cross-sections of wire or metal 45 which may be employed, among others, in making nut-locks of this character.

The nut-lock 1 (shown in Figs. 1, 2, and 3) is simply a one-revolution helix made of metal

5 of suitable cross-section bent to correspond with the pitch of the thread of the bolt to which it is to be applied and having its abutting ends 2 bent at right angles to the general plane of the helix, so that they project therefrom in a direction parallel to the axis of the bolt when the nut-lock is placed thereon. As shown in these figures, the device is 60 made of metal of a cross-section which is externally rectangular, but is made with a V-shaped or thread-like internal edge 3, corresponding in shape to the thread of the bolt. The ends 2 of the ring are, furthermore, here- 65 in shown as made of less than the full depth of the section, so that bending them does not affect said V-shaped inner edge, but permits the latter to follow the thread closely to the extreme ends of said edge.

70 In the construction shown in Figs. 4, 5, and 6 the nut-lock 4 is made of the same general form as that shown in my previous patent, No. 614,835, patented November 29, 1898, the wire being bent into a helix of something 75 more than a complete circumference, with its end portions overlapping, as shown. The extremities 5 of said ends are, however, bent at right angles to the body of the nut-lock or parallel with the axis of the inserted bolt, as 80 in the construction first described, instead of being permitted to project outwardly, as in said prior patent. The metal used for this nut-lock 4 is of similar cross-section to that of the device shown in Figs. 1, 2, and 3, and 85 its extremities 5 are reduced in depth in the same manner and for the same purpose as before.

75 The nut-lock 6 (shown in Figs. 7, 8, and 9) is identical with that shown in Figs. 4, 5, and 6, except that the metal is additionally strengthened by increasing the stock on its outer edge, which is herein shown as also beveled off to a V shape. It will, however, be understood that any suitable cross-section 90 of metal may be employed in making nut-locks in accordance with my invention besides the cross-section heretofore described, and in Fig. 10 I have illustrated several more 95 of the many forms which may be employed, and it will also be understood that while the reducing of the extremities of the wire to less than its full depth, as shown in Figs. 1 to 9, is of advantage in that it leaves the

thread-like inner edge of the metal unbent and definite, the invention is, nevertheless, not limited to this construction.

The bending of the extremities of the metal at right angles to the body portion of the nut-lock not only affords in practice a better purchase for the expander or other tool used in applying or removing the device, but brings said ends down close to the bolt, where they are less liable to catch and lacerate the person or clothing of people moving in the vicinity of the nut-lock or to catch and hold straw and lint or other material which may be brought into contact therewith.

15 I claim as my invention—

1. A nut-lock consisting of a coiled piece of spring metal adapted to fit between the threads of a bolt and having its extremities bent parallel to the axis of the bolt, substantially as described.

2. A nut-lock comprising a coiled piece of spring metal whose ends overlap each other and are bent at right angles to the body of the device at their extremities, substantially as described.

25 3. A nut-lock consisting of a coiled piece of spring metal having a thread-like inner edge and overlapping ends, the extremities of said ends being reduced in depth and bent at right angles to the body of the device, substantially as described.

In testimony that I claim the foregoing as my invention I affix my signature, in presence of two subscribing witnesses, this 17th day of January, A. D. 1900.

WILLIAM H. CARRUTHERS.
